UNITED STATES PATENT OFFICE.

GEORGE B. HURLBURT, OF MIDDLETOWN, CONNECTICUT.

WHEEL.

No. 873,048.

Specification of Letters Patent.

Patented Dec. 10, 1907.

Application filed April 6, 1907, Serial No. 366,674.

To all whom it may concern:

Be it known that I, GEORGE B. HURLBURT, a citizen of the United States, residing at Middletown, in the county of Middlesex and 5 State of Connecticut, have invented certain new and useful Improvements in Wheels, of which the following is a specification, reference being had therein to the accompanying drawings.

10 My invention relates to new and useful improvements in wheels, and refers more particularly to steering wheels for launches and other small vessels; its object being to provide a simple and compact device which 15 will be strong and durable, neat and pleasing in appearance, and can be readily assembled.

To these, and other ends, my invention consists in the wheel having certain details 20 of construction and combinations of parts as will be hereinafter described and more particularly pointed out in the claims.

Referring to the drawings, in which like numerals of reference designate like parts in 25 the several figures; Figure 1 is a transverse sectional elevation of my improved device; Fig. 2 is a rear elevation of the base plate; and Fig. 3 is an elevation of the hub of the wheel looking from the left of Fig. 1.

30 In the practice of my invention I provide a wheel 1 having a central hub 2; integral radiating arms 3; and posts 4 projecting radially outside of the rim of said wheel, and to which the handles 5 are secured. Fixed 35 to the hub of said wheel is the drum 6. In the drawings the means shown for securing said hub and drum are the pins 7 which project laterally from the hub 2 into one end of said drum. The wheel and drum are rotatable upon a pin 8 which has a solid head 9 lying within a recess in the face of said hub and removably secured at its other end in a plate 10 by a pin 11, which lies in a groove 12 in the back of said plate and passes diametrically through a hole in said pin near the end thereof. The plate 10, as shown herein, 45 has parallel side edges, but it may be circular or any other shape that would be most convenient, and is preferably secured to a fixed 50 part by screws which pass through holes 13 provided to receive them. Integral with said plate is a boss 14 which is designed to support the inner end of the drum 6.

The devices of this character in common 55 use have a bolt which is first threaded into the plate and then secured against rotation

either by a nut or other means, after which the wheel is then mounted on the bolt and held against accidental displacement by a nut which is threaded thereon against a 60 shoulder. This method of construction is highly undesirable, because to take down the wheel and drum necessitates the dismantling of all of the mechanism, that is, the nut must first be taken off, after which the wheel and 65 drum are separately dismounted and then the plate removed. A further objection arises from the exposed nut in that it frequently tears the clothing and body of a person who accidentally is brought in contact 70 therewith, and at times it becomes loosened and drops off. In my improved construction, herein described, the wheel and drum are inseparably secured together and the mechanism is assembled by first passing the 75 pin through the wheel and drum and afterwards the plate where it is secured by means of a fastening pin. The whole mechanism is then permanently secured by the attachment 80 of the plate 10. Thus, it will be noted, that 80 the pin, plate, wheel and drum are all operatively connected with each other before the wheel is mounted and there are no exposed parts liable to become separated, or sharp edges to injure anything brought in contact 85 therewith.

There are minor changes and alterations that can be made within my invention, aside from those herein suggested, and I would therefore have it understood that I do not 90 limit myself to the exact construction herein shown and described, but claim all that falls fairly within the spirit and scope of my invention.

Having described my invention, what I 95 claim as new and desire to secure by Letters Patent, is:

1. In a device of the character described, the combination with a wheel having laterally projecting pins upon the hub thereof; 100 a drum connected with said wheel and secured by said pins; a plate; a headed bolt passing through the hub of said wheel and said drum, and separably secured to said plate.

2. In a device of the character described, the combination with a wheel having pins connected with the hub thereof; a drum secured to said hub by said pins; a plate; a headed pin passing through said hub and 110 drum with the head thereof engaging the exposed side of said hub; and a fastening pin

105

110

for separably securing the aforesaid pin to said plate.

3. In a device of the character described, the combination with the wheel 1 having the hub 2 integral therewith; pins 7 forming part of said hub and projecting laterally therefrom; a drum 6 mounted on said pins; a plate 10 having a boss 14 thereon upon which said drum is rotatable; a pin 8 having

a head 9 thereon; and means, as a pin 11, 10 for separably securing said pin to said plate.

In testimony whereof I affix my signature in presence of two witnesses.

GEORGE B. HURLBURT.
